Fred P. Gorin
ATTORNEY

UNITED STATES PATENT OFFICE.

ERIC M. SMITH, OF SEATTLE, WASHINGTON.

TOOL HOLDER.

1,410,131.

Specification of Letters Patent. Patented Mar. 21, 1922.

Application filed November 15, 1920. Serial No. 424,315.

To all whom it may concern:

Be it known that I, ERIC M. SMITH, a citizen of the United States, and residing at Seattle, in the county of King and State of Washington, have invented certain new and useful Improvements in Tool Holders, of which the following is a specification.

This invention relates to improvements in tool supporting devices, more especially to such devices attached to the person.

The principal object of the invention is to provide a device of this character which is simple in construction, easy to operate and may be readily attached to the clothes of the operator.

These and other objects will appear as my invention is hereinafter more fully set forth in the following specification, shown in the accompanying drawings and finally 20 pointed out in the appended claims.

In the drawings:

Fig. 1 is a front elevation of the holder, Fig. 2 is a front elevation of the holder showing the device in a closed or locked 25 position.

Fig. 3 is a section upon the line 3—3 in Fig. 2, a hammer also being shown in dotted lines, retained in the said holder.

Fig. 4 is a fragmentary section on the 30 line 4—4 in Fig. 2, a hammer also being shown in dotted lines, retained in the said holder.

My improved device comprises a body portion consisting of a wire 10 having the 35 lower ends 11 thereof extending from the longitudinal portion bent upwardly as in Fig. 4 for the reception of a tool. The body portion 10 is preferably adapted to be attached to some convenient part of the workman's apparel such as his belt, or the waist-line of his trousers, by screws 12 passing through a metal clip 13, revolvably mounted on the horizontal portion of the wire 10 and nuts 14.

15 is a plate whose longitudinal edges are turned inwardly around the longitudinal portions of the wire 10, said wire being journaled in the said formed edges generally shown at 16. Disposed near the upper edge 50 of the plate 15 and in the central part thereof is a struck out portion 17, which is crimped around the lateral portion of a wire formed jaw 18, whose ends are formed with an offset 19, abutting the plate 15 as shown 55 in Figs. 3 and 4 and the ends thereof passing

through holes 20 in the plate 15, said ends being turned downwardly, thereby making the said wire jaw rigid to the plate 15.

21 is a tension spring whose one end is attached to the plate 15 in any suitable 60 manner, generally shown at 22 in Fig. 1 and whose other extremity is in the form of a hook 23, which passes through an eye 24, at one end of a link 25, the other end of the link being revolvably attached to the 65 horizontal portion of the wire 10. In the clip 13 there is a cut out portion 26 which receives the link 25. 27 is a U formed spring which is rigidly attached to the plate 15 by the struck out portions of the plate 70 15 which are crimped, as indicated at 28, around the lateral portion of the said spring. Near the bottom ends of the longitudinal portions of the spring 27 there are bent out portions 29, the extreme ends of the said 75 spring being formed so as to provide suitable finger grips 30. To keep the spring 27 from moving outwardly from the plate 15, there has been provided struck out portions 31 whose free ends pass over the longitudinal portion of the said spring. Extending from the lower end of the longitudinal edges of the plate 15 and integral therewith are jaws 32 as shown in the solid lines in Figs. 3 and 4. In dotted lines in Figs. 3 and 4 80 85 is a hammer 33. Intermediate the jaw 32 and the turned edge 16 is a cut-out portion of the edge 16 which partially encircles the wire 10 as shown at 34 in Figs. 3 and 4.

In the operation of a device as herein described, it can readily be seen that when a tool has been inserted in the holder as in Fig. 3 and the said tool moved downwardly against the auxiliary jaws 32 which it will be remembered are integral with the slidable 90 locking jaw 18, to move said jaw downwardly a pre-determined distance at which time the bent-out portion 29 of the U spring 27 comes into engagement with the bottom side of the portions 11 of the wire 10 as 100 shown in Figs. 2 and 4, thereby retaining the tool in the holder as shown in Fig. 4. To return the locking jaw to its normal position this is accomplished by placing the thumb and finger on the grips 30 of the 105 spring 27 and pressing them inwardly which of course will allow the spring 21 to move the locking jaw upwardly to its normal position as shown in Figs. 1 and 3.

While I have shown a particular form of 110

embodiment of my invention, I am aware that many minor changes therein will readily suggest themselves to others skilled in the art, without departing from the spirit 5 and scope of my invention. I therefore desire to avoid being limited to the exact form shown and described.

Having described my invention, what I 10 claim as new and desire to protect by Letters Patent, is:

1. A tool holder comprising a wire body portion, supporting jaws stationary with the said body portion, a locking jaw normally in unlocked position and slidably mounted on 15 said body portion and adapted to coact with the supporting jaw.
2. A tool holder comprising a wire body portion, tool supporting jaws projecting therefrom, a locking jaw slidably mounted 20 on said wire body portion, and thereby adapted to be moved into and out of locking position and means for retaining the said locking jaw in locked position.
3. A tool holder comprising a wire body

portion, tool supporting jaws projecting 25 therefrom, a locking jaw slidably mounted on said wire body portion, and thereby adapted to be moved into and out of locking position and means for retaining the said locking jaw in locked position, including a 30 spring member.

4. A tool holder comprising a wire body portion, means for attaching the same to a garment, tool supporting jaws projecting from the body portion, a locking jaw normally in unlocked position and slidably mounted on said body portion and lockable by a downward movement, means for retaining the said locking jaw in locked position, and means for returning said locking jaw to 40 a normal position.

In testimony whereof I affix my signature in the presence of two witnesses.

ERIC M. SMITH.
